David Davison, Baltimore, Md.

Application September 3, 1953, Serial No. 26,701

Term of patent 7 years

(Cl. D55—1)

To all whom it may concern:

Be it known that I, David Davison, a citizen of the United States of America, residing at Baltimore City, State of Maryland, have invented a new, original, and ornamental Design for a Snowball Machine, of which the following is a specification, reference being had to the accompanying drawing, forming a part thereof, in which:

Figure 1 is a front view in elevation of a snowball machine showing my new design;

Figure 2 is a side elevation of Figure 1; and

Figure 3 is a plan view of Figure 1.

The other side not shown is substantially like the side shown.

I claim:

The ornamental design for a snowball machine, as shown and described.
